UNITED STATES PATENT OFFICE.

JOHN HARRIS, OF LAKEWOOD, OHIO.

GRINDING MACHINE.

Application filed April 9, 1921. Serial No. 459,919.

To all whom it may concern:

Be it known that I, JOHN HARRIS, a citizen of the United States, residing at Lakewood, in the county of Cuyahoga and State of Ohio, have invented a certain new and useful Improvement in Grinding Machines, of which the following is a full, clear, and exact description, reference being had to the accompanying drawings.

10 This invention relates to grinding machines and, in the embodiment shown herein, is particularly well adapted for finishing the ends of objects such as tips for blow-pipes, which ends are liable to be provided 15 with burrs, projections or inequalities.

It is the general purpose and object of the invention to provide a machine of this character which is simple and economical of production, and which is particularly efficient in 20 operation. Further and more limited objects of the invention will be set forth hereinafter and are realized in and through the combinations of elements embodied in the 25 claims hereto appended.

25 In the drawings, Fig. 1 represents a side elevation of a machine constructed in accordance with my invention; Figs. 2, 3 and 4 sectional views corresponding, respectively, to the lines 2—2, 3—3, and 4—4 of Fig. 1, the worm gear, the rotating platform and the track being shown in elevation in Fig. 3; and Fig. 5 an enlarged sectional detail through one of the sockets in which the tips are mounted, showing the manner of 35 supporting the tip therein and upon a track therebeneath.

Describing the various parts by reference characters, 1 and 2 denote a pair of end uprights, each of which may be a metal channel, as shown, and supporting at their upper ends a cross member 3, which may also be of channel shape, with its flanges projecting upwardly, and conveniently secured to the members 1 and 2 by angle brackets 4.

45 Supported by the said members 1 and 2 through angle brackets 5 is an intermediate cross member 6. The lower ends of the uprights may be braced by strut members 7 secured thereto and to the floor or foundation and may also be connected by a rod 8.

Carried by the uprights 1 and 2, below the member 6, is a pan-like receptacle comprising the bottom 9 and the side and end walls 10.

55 11 denotes a motor mounted upon a base 12, shown as supported by the top member

3. The shaft 13 of the motor is provided with a pulley 14 by means of which and a pulley 15 and belt 16, a shaft 17 is driven, the said shaft being shown as journaled in supports 18 interposed between and carried by the members 3 and 6. The shaft 17 is provided at the end opposite the pulley 15 with a worm 17^a meshing with a worm gear 19 upon a vertical shaft 20 journaled in the members 3 and 6 and projecting downwardly into the pan, through a cover 10^a partly closing the top of the same. The lower end of the shaft 20 is provided with a grinding wheel 21, preferably of carborundum. The 70 shaft is provided also with a bevel pinion 22 meshing with a bevel gear 23 on a shaft 24 journaled in a U-shaped bracket 25. The shaft 24 is provided at the end opposite the gear 23 with a pinion 26 meshing with a 75 pinion 27 on a stud 28, the latter pinion meshing with a gear 29 on a shaft 30, the said shaft being provided with a worm 31 meshing with a worm gear 32, rigid with a vertical shaft 33 mounted in the members 3 80 and 6 and having its lower end provided with a rotary platform 34.

The platform 34 is preferably in the shape of a disk having a peripheral series of bores therethrough, each having an upwardly extending sleeve 36 and constituting sockets.

85 Supported on a suitable bracket 37 and adjustable standards 38—38^a is an arcuate track comprising an upwardly inclined member 39 and a substantially horizontal member 40. The track is positioned beneath the platform 34, beneath the sockets 36, with its central or intermediate portion supported by the said bracket. The portion or member 39 of the track extends from the bracket 37 to a point slightly above the upper surface of the grinding wheel 21, having its upper end supported by the adjustable standard 38. The portion or member 40 extends from the bracket 37 to a point adjacent to but positioned slightly below the upper surface of the wheel 21 where it is supported by the adjustable standard 38^a. These standards are mounted in the pan 9 and serve to adjust the ends 90 of the track 39, 40 to compensate for the wear on the grinding wheel.

95 With the parts constructed and arranged as described power will be transmitted from the motor shaft 13, through pulleys 14 and 15 and belt 16 to the shaft 17 and thence by the worm 17^a and worm gear 19 to the shaft 100 110

20, driving the grinding wheel 21. By means of the reducing-gear connections between the shaft 20 and the platform 34, the latter will be driven at a slow speed, as 5 compared with the grinding wheel 21, in the direction indicated by the arrow on Fig. 2. The operator will insert the tips into the sleeves 36 as the platform revolves, the lower end of each tip being supported by 10 the upwardly inclined track member 39 and delivered therefrom upon the upper surface of the grinding wheel 21. As the tips travel up the track section 39, they will be given a preliminary grinding by virtue of the presence of particles of abrasive material on said 15 section, such particles being removed from the wheel 21 during its operation. The tips 41 will fit loosely within their sleeves 36 and openings 35 so that their lower ends may be 20 pressed by gravity into engagement with the rapidly rotating grinding wheel. By the time when the tips shall have traveled across the surface of the grinding wheel, the burrs or other projections on the lower ends 25 thereof will have been removed, and the tips thus finished may be removed as soon as they again reach the track member 39; or the operator may remove them as they are brought to him along the track member 39 30 by the rotation of the platform; the operator replacing the finished tips with unfinished ones.

In operation the foregoing machine has 35 been found to be particularly efficient, finishing off the ends of some sixty tips per minute and requiring the attention of but a single attendant. Furthermore, as will be 40 evident from the drawing, the machine by which this result is accomplished is extremely simple and economical of production. It will also be noted in this connection that the grinding action takes place over the entire surface of the wheel 21, hence the wheel is 45 worn down evenly and does not require redressing.

After the tips have had their lower ends ground in the manner described, they may be inserted into a standard type of burnishing machine 42, mounted on the upright 2, the work-receiving bushing of such machine being indicated at 43. The pan 9 serves to collect the filings or particles ground from the ends of the tips. If desired, the track member 40 may be dispensed with, in which 50 case the tips will be dropped into the pan as they are carried from the upper surface of the grinding wheel by the rotary platform.

Having thus described my invention, what I claim is:

60 1. In a machine of the character described,

the combination of a horizontally arranged grinding wheel, means for driving the same, a horizontally arranged rotatable platform above and overlapping said grinding wheel and provided with a plurality of sockets for the reception of articles adapted to be carried by said platform above the said grinding wheel and in engagement with the upper surface of the latter, a track member below the said sockets and adapted to support the 65 lower ends of the articles placed therewithin, said track member being inclined upwardly with its delivery end substantially flush with the upper surface of said wheel, and means for driving said platform. 75

2. In a machine of the character described, the combination of a vertical shaft, a grinding wheel carried thereby, means for driving said shaft, a second vertical shaft, a rotary platform mounted on the second shaft above 80 and overlapping the upper surface of the grinding wheel, the said platform having a peripheral series of sockets adapted to support articles therein with their lower ends in engagement with the upper surface of the 85 grinding wheel, speed reducing connections between the said shafts, and a segmental track beneath the portion of the platform extending beyond the grinding wheel and adapted to support the articles in said sockets, one end of said track extending upwardly in order to deliver the articles carried by said sockets to the upper surface of 90 said grinding wheel, and the other end of said track being positioned below the upper 95 surface of the grinding wheel and adapted to receive the ground articles.

3. In a machine of the character described, the combination of a substantially horizontal grinding wheel, a rotary platform above 100 and overlapping the upper surface of the grinding wheel, the said platform having a series of sockets adapted to support articles therein with their lower ends in engagement by gravity with the upper surface of the 105 grinding wheel, a track beneath the portion of the platform extending beyond the grinding wheel and adapted to support the articles in said sockets, one end of said track extending upwardly in order to deliver the articles carried by said sockets to the upper surface of said grinding wheel, the other end of said track being positioned below the upper surface of the grinding wheel and adapted to receive the ground articles, and 110 means for driving the said wheel and platform. 115

In testimony whereof, I hereunto affix my signature.

JOHN HARRIS.
